(57) **CLAIM**

The ornamental design for a high pressure gas storage unit, as shown and described.

DESCRIPTION

FIG. 1 is a front, right side, top, perspective view of a high pressure gas storage unit showing our new design;

FIG. 2 is a front, elevation view of the high pressure gas storage unit illustrated in FIG. 1;

FIG. 3 is a rear, elevation view of the high pressure gas storage unit illustrated in FIG. 1;

FIG. 4 is a right side, elevation view of the high pressure gas storage unit illustrated in FIG. 1;

FIG. 5 is a left side, elevation view of the high pressure gas storage unit illustrated in FIG. 1;

FIG. 6 is a top, plan view of the high pressure gas storage unit illustrated in FIG. 1;

FIG. 7 is a bottom, plan view of the high pressure gas storage unit illustrated in FIG. 1; and,

FIG. 8 is an enlarged view of the selected portion identified in FIG. 3.

The broken lines shown in the drawings depict portions of the high pressure gas storage unit that form no part of the claimed design. The dot-dash broken lines surrounding details shown in FIGS. 3 and 8 are for the purpose of annotating the enlarged views only and form no part of the claimed design.
